[57] **CLAIM**

The ornamental design for a spout, as shown and described.

DESCRIPTION

FIG. 1 is a perspective view taken from the top and front and right side of a spout showing my new design; FIG. 2 is a top plan view thereof; FIG. 3 is a front elevation view thereof; FIG. 4 is a bottom plan view thereof; and, FIG. 5 is a right side elevation view thereof, the left side elevational view being the mirror image of the right side.
